UNITED STATES PATENT OFFICE.

GEORG O. HEINRICH, OF LITTLE ROCK, ARKANSAS.

SUPPLEMENTAL STEP FOR CARS.

1,077,139.

Specification of Letters Patent. Patented Oct. 28, 1913.

Application filed March 11, 1913. Serial No. 753,554.

To all whom it may concern:

Be it known that I, GEORG O. HEINRICH, a subject of the Emperor of Germany, residing at Little Rock, in the county of Pulaski and 5 State of Arkansas, have invented new and useful Improvements in Supplemental Steps for Cars, of which the following is a specification.

The present invention relates to an extensible supplemental step for the main steps of a railway car or the like.

In carrying out the invention it is my purpose to provide a supplemental step which is adapted to be normally sustained 15 below the lower main step, but which may be readily projected outwardly of the said lower main step and sustained in an extended position to provide an additional step for the main steps.

Another object of the invention is the provision of simple but effective means for operating the supplemental step to rigidly sustain the same in its lowered or operative position as well as in its folded position beneath the lower main step.

With the above recited objects in view, and others which will appear as the nature of the invention is more fully understood, the improvement resides in the construction, 30 combination and operative arrangement of parts set forth in the following description and falling within the scope of the appended claim.

In the drawing there has been illustrated 35 a simple and preferred embodiment of my improvement, and in which:

Figure 1 is a perspective view of a portion of a car provided with the improvement, Fig. 2 is a detail side elevation of 40 the same, the supplemental step being shown in its lowered position, Fig. 3 is a similar view but illustrating the step in its folded or raised position, Fig. 4 is an enlarged sectional view illustrating the arrangement of 45 the operating lever with the mechanism for operating the supplemental step, Fig. 5 is a detail vertical longitudinal sectional view on the line 5—5 of Fig. 1, Fig. 6 is a detail perspective view of the elements connected 50 with the supplemental step and designed for raising and lowering said supplemental step, and Fig. 7 is a detail sectional view on the line 7—7 of Fig. 2.

In the following description, the improvement will be referred to in connection with

the steps of an ordinary railway coach, the drawings illustrating the improvement in such application, but it is to be understood that the device may be employed with equal efficiency upon street cars, omnibuses, and upon all other vehicles or contrivances wherein the employment of an extension supplemental step is desired.

Referring now to the drawings in detail, the numeral 1 designates the coach which 60 has its platform provided with the usual main steps 2, the steps proper having the usual side connecting members or carriages 3.

The numeral 4 designates the supplemental step. This step is of a width approximately equaling the width of the lower main step 2, but the said auxiliary step is preferably of a greater length than said main step. The step 4 has its opposite 70 ends adjacent its rear edge provided with elongated depressions 5 and the said step preferably has its angular face provided with transversely arranged channels 6 which communicate with the depressions 5 and which are of a length equaling that of the depressions 5. The channels 6 and depressions 5 provide substantially T-shaped openings, whereby the heads 7 of studs 8 may be arranged within the channels, while the 75 studs proper project through the depressions 5. The projecting studs are each secured to one end of a link 9, the said link being centrally provided with an elongated slot 10 and has its opposite or free end pivotally connected with the carriages 3 adjacent the lower and outer edges thereof, or at the point of connection of the lower main step 2 with the said carriages 3, as indicated by the numeral 11.

Pivots secured, as at 12, to the ends of the auxiliary step 4, forward of its depressions 5, are arms 13 and 14 respectively. These arms, adjacent their pivots 12 are provided with elongated slots 15, and passing through the said slots 15 and through the slots 10 of the links 9 are the rounded shanks of oppositely headed members 16. The arms 13 and 14 are provided with a connecting member 17, which is arranged at 95 the free end of the arm 14, and the arm 13 it will thus be noted, is of a greater length than the arm 14. Both the arms 13 and 14 are arranged at an angle substantially similar to the pitch of the main steps 2. The 110

arm 14, adjacent its connection with the member 17 is bent to assume a substantially horizontal position, and the underface of each of the arms at the juncture with the 5 said horizontal portion and the angular arm proper is provided with a notch or recess 18 which is adapted to receive a headed pintle 19, when the step is in its lowered position, and so to limit the downward and outward 10 movement of the supplemental step 4, as well as to prevent the inward movement or folding of the said supplemental step. The lower edge of the arm 14 is adapted to travel on the pintle 19 which is secured in 15 any desired manner to the outer carriage 3 of the main steps 2. If desired, a similar guiding pintle or roller member may be provided for the arm 13, and the said arm may be likewise notched to perform the 20 functions just stated.

The arm 13 has its free end pivotally connected with the lever 20, the said lever, in turn, being pivotally connected to the end 25 of the car 1, and this lever is adapted to be guided within a segmental strap 21 which is also secured to the end of the car. The strap may be, and preferably is, provided with two spaced openings or depressions 22 and 23 respectively, and the lever 20 is preferably provided with a spring dog 24 which is adapted to be received within the depression 22 when the lever is swung to lower the supplemental step 4, and to be received 30 within the depression 23 when the supplemental step is folded below the lower main step. It is, of course, to be understood that 35 an ordinary spring pressed pawl having an

operating rod and handle may be connected with the lever 20, and that the segment 21 40 may be provided with spaced teeth between which the dog is adapted to engage when the supplemental step is in its lowered position or in its raised or folded position.

Having thus described the invention, what 45 I claim as new is:

The combination with a vehicle having steps, of an auxiliary step adapted to normally lie beneath and against the lower main step, said auxiliary step having its ends 50 provided with substantially T-shaped recesses, head members within the recesses, a link connected with each of the said headed members and pivotally connected to the lower main step, said link being centrally 55 provided with a slot, arms pivotally connected with the ends of the auxiliary step forward of its slots, said arms having elongated openings, an oppositely headed member arranged within the openings of the 60 arms and the openings of the links, a headed pintle arranged upon the main steps and adapted to provide a rest for the arms, one of said arms being notched to provide a pocket for one of the headed pintles when 65 the auxiliary step is lowered, a connection between the arms, and a pivoted operating lever connected with one of the arms.

In testimony whereof I affix my signature in presence of two witnesses.

GEORG O. HEINRICH.
